AUTOMATIC LOCK SLIDER FOR SLIDE
FASTENERSGideon Sundback, Meadville, Pa., assignor to
Talon, Inc., Meadville, Pa., a corporation of
Pennsylvania

Application August 3, 1946, Serial No. 688,213

12 Claims. (Cl. 24—205.14)

1

This invention relates to an automatic lock slider for slide fasteners. It is customary to provide slide fasteners with a slider which is normally and automatically locked to the chain or stringers to prevent unintended opening of the fastener, but which is freely movable either to close the zipper or to accomplish intended opening of the fastener. Such sliders usually have a spring-pressed locking point or prong normally held in locking position, blocking the channel in the slider through which the interlocking elements pass. The prong is automatically removed from locking position against the force of the spring whenever the customary handle or pull tab is pulled in the direction tending to open the fastener.

Such known slide fasteners are satisfactory within their inherent limitations, but have several disadvantages. They depend upon the force of the spring to effect locking. Therefore if the slider locks securely, a strong spring is required. Such a spring constantly urges the locking prong so firmly against the interlocking elements of the chain that when the fastener is closed, the prong ratchets roughly over the interlocking elements. This has several undesirable results. It is objectionably noisy. It makes the slider rough to operate. The prong wears on the interlocking element and rapidly wears out its locking point. When used with colored fasteners, the point also removes the paint or chemical finish from the interlocking elements. On the other hand if it is sought to eliminate these disadvantages by using a light spring, the locking action is uncertain and insecure.

One of the objects of the present invention is to provide an improved form of automatic lock slider which is certain and secure in its locking action, and in which ratcheting when closing the fastener is greatly reduced or substantially eliminated. More specifically it is an object to provide a locking member which is normally held in an incipient or potential locking position and is moved automatically to locking position whenever the slider tends to open the fastener without opening action of the pull tab.

Another object is to provide an improved form of locking means which engages opposite sides of an interlocking element, as distinguished from the usual locking element which engages only one side.

Another object is to provide an improved form of lock slider which will be economical to manufacture and which will have a long locking life, it being the fault of many locking sliders that

2

they soon lose their locking characteristics even though they remain serviceable as non-locking sliders.

Still another object is to provide an improved form of locking element particularly suitable for use in die-cast sliders and which can be readily and cheaply assembled in a die-cast slider body after completion of the casting operation.

Another object is to provide an improved lock slider in which the locking force increases with increasing force tending to open the fastener.

In the accompanying drawings:

Fig. 1 is a perspective view of a slide fastener embodying one form of my invention;

Fig. 2 is an elevation of the bottom end of the slider shown in Fig. 1, drawn on an enlarged scale;

Fig. 3 is a section of the slider on the line 3—3 of Fig. 2 showing the locking parts of the slider in their normal or neutral position;

Fig. 4 is a similar section showing the locking parts in locked position; and

Fig. 5 is a similar section showing the locking parts in unlocked position.

25 Referring to the drawings, the slide fastener consists of a pair of stringers or chains each including a fabric tape 10, to one edge of which is secured a row of interlocking elements 12. The fastener is opened or closed by a slider 14 which embraces both rows of interlocking elements and has a Y-shaped channel 16 (Fig. 2) for the passage of elements through it, a pair of cam faces 18 (Fig. 1) for progressively interlocking the elements when the slider is moved in one direction, 30 and a diamond or wedge 20 for progressively disengaging the elements to open the fastener when the slider is moved in the opposite direction.

The tapes may be permanently secured together at the lower or closed end of the fastener 40 by a connecting clip 22, called a bottom stop. The slider body is provided with a bail or loop 24 to which is attached a pull tab 26 for moving the slider along the tapes. The slider body, including the bail, is preferably diecast as an integral piece including an upper face or plate 27, a lower plate 28, and a connecting wedge or diamond 20. As so far described the fastener is well known. It is also known to provide various forms of locking devices which automatically prevent 45 unintended opening of the fastener by locking the slider to the chain except when the slider is operated by the pull, in which case it is automatically unlocked.

In accordance with my invention I provide an 50 improved locking means including members pro-

jecting into the passage 16 from opposite sides, blocking passage of the interlocking elements and engaging one or more elements on opposite sides simultaneously. The locking members are normally disposed in a neutral position and are automatically moved into locking position whenever any force other than that exerted by the pull 26 tends to move the slider in the opening direction.

A preferred form of construction for accomplishing this is the following. A longitudinal slot 30 is formed in the slider body, extending through one end of the bail, entirely through a part of the upper plate 27, through the point of the diamond and part way through a portion of the lower plate 28. This forms a slot in the upper plate and a groove in the lower plate, which function as longitudinal guideways for spring arms 36 and 37 carrying locking prongs 39 and 40. Preferably the spring arms are opposite ends or forks of a Y-shaped spring member 41 which has a tail 42 slidably mounted in a third longitudinal guideway 43 drilled or cast in the diamond. The entire spring member is so formed and disposed that the locking points 39 and 40 normally just touch opposite sides of an interlocking element as indicated in Fig. 3. This is a neutral position, neither locked nor entirely free, but the prongs are held in an incipient or potential locking position from which they are moved to locked position whenever the slider tends to move in the opening direction otherwise than under the force of the pull tab. The end of the arm 36 is formed into a hook 44 lying generally within the end of the bail but normally projecting inside the loop as shown in Fig. 3 and shaped to conform to this portion of the bail. As shown best in Fig. 3, the part of the slot 30 located in the bail terminates in a sloping surface forming a cam face 45 designed to cooperate with the end of the hook 44 which has a surface parallel to the cam surface and adjacent to it, so that when the slider body is moved to the right as seen in Fig. 4 and the locking spring is held stationary, the cam face urges the spring arm and its locking point 39 toward the interlocking elements. The free end of the opposite spring arm 37 is formed with an inclined tip 47 which projects into an inclined hole through the lower face plate 28 of the slider body. One side 48 of this hole acts as a cam face which, when the slider body is slid to the right and the spring arm held stationary, as seen in Fig. 4, forces the locking point 40 toward the interlocking elements. The other side 50 of the inclined hole acts as a cam face which, when the spring arm is moved to the right with respect to the slider body as seen in Fig. 5, moves the locking point 40 out of engagement with the interlocking elements and out of the slider passage 16.

The slider is normally as shown in Fig. 3. The locking points 39 and 40 engage the opposite sides of the interlocking elements with insufficient force to cause secure locking action, but with just enough force to hold the locking spring stationary on the chain if the slider tends to move to the right as seen in Fig. 3, in any opening movement other than that caused by the pull tab. When this occurs, the cam faces 45 and 48 press the locking prongs into the channel 16 between the interlocking elements as shown in Fig. 4, and lock the slider by blocking passage of the elements through the slider. It will be observed that if the force tending to move the slider in the opening direction is increased, the cam faces increase the force with which the locking points are held in contact with the interlocking elements, thus in-

creasing security of the locking action in proportion to the opening force. When the pressure on the slider tending to open the fastener is released, or when the Y-spring is moved to the right with respect to the slider body as seen in Fig. 5, the arms with their locking prongs 39 and 40 under spring tension lift away from the interlocking elements into neutral position as shown in Fig. 3. Whenever the fastener is opened by the pull, the pull occupies the position shown in Fig. 5, the force along the pull having a transverse component represented by the vector 52 and a longitudinal component which is represented by the vector 54. The transverse component flexes the arm 36 and moves the locking member 39 out of engagement with the interlocking elements and entirely out of the passage 16. The longitudinal component slides the spring member 41 to the right from the position shown in Fig. 4 to the position shown in Fig. 5. As this occurs the spring arm 37 is flexed by the cam 50 to move the locking prong 40 out of the slider passage. When the hook 44 has been pushed into the loop far enough to lift the prongs 39 and 40 out of contact with the interlocking elements the pull tab engages the loop to move the slider. If desired each spring arm may carry a pair of locking prongs 39 or 40 which simultaneously engage a pair of interlocking elements 12, thus enhancing the security of the locking action and prolonging the life of the locking members.

When it is desired to close the fastener, the pull is operated in the position shown in Fig. 1, where it draws the slider in the direction to close the fastener, leaving the locking spring free. Since the locking element is in the position shown in Fig. 3, the locking points can slide over the interlocking elements, alternately moving between the positions shown in Fig. 3 and Fig. 5. Due to the fact that the pressure on the elements is very light, even with the locking points in the position shown in Fig. 5, ratcheting is very light and does not remove the finish from the elements or cause rough operation of the slider.

In practice the slider body may have the slot 30 and guide hole 43 formed by cores or projections in the die in which it is cast, and the slanting hole forming the cams 48 and 50 may either be cored or may be pierced in the finished casting. The spring member 41 may be stamped out of spring material. It is inserted in the finished slider body by sliding it into the open end of the slot, the arm 37 being flexed sufficiently to let the inclined end 47 enter the slot 30. The inclined end snaps into the slanting hole, permanently retaining the spring in the slider body.

Thus the slider has a pair of locking members which engage opposite faces of an interlocking element, the pull disengages one locking element from the row of interlocking elements and moves it out of the slider passage, simultaneously sliding the locking element along the slider longitudinally. The other locking element is moved out of locking position in response to the longitudinal movement of the first locking element under influence of the pull, due to the cam 50. The tail 42 of the Y-shaped spring 41 guides the spring in its longitudinal movement and confines the effect of the component 52 to flexing the spring arm 36. This prevents the whole member from rotating counterclockwise as seen in Fig. 3, which would otherwise set the lower locking member 40 more firmly against the interlocking elements 12 instead of removing it from them. However the guiding tail 42 may

not be necessary in all cases, and in some instances I may omit it.

I claim:

1. A slide fastener comprising in combination, a pair of rows of interlocking elements, a slider having a passage for the rows and adapted when moved in one direction along the rows to interlock the rows to close the fastener and when moved in the opposite direction along the rows to disengage the rows to open the fastener, a locking member movable longitudinally in the slider and adapted to project into the passage, means carried by the slider resiliently holding the locking member in a fixed position projecting into the path of the interlocking elements through the passage, and means responsive to engagement of an interlocking element with the locking member and subsequent longitudinal movement of the slider along the rows in the opening direction for moving the locking member further into said path.

2. A slide fastener comprising in combination, a pair of rows of interlocking elements, a slider having a passage for the rows and adapted when moved in one direction along the rows to interlock the rows to close the fastener and when moved in the opposite direction along the rows to disengage the rows to open the fastener, a locking member movable longitudinally in the slider and adapted to project into the passage, means carried by the slider resiliently holding the locking member in a fixed position projecting into the path of the interlocking elements through the passage and an inclined cam for moving the locking member further into the said path in response to engagement of an element with the locking member and to subsequent longitudinal movement of the slider with respect to the locking member in the opening direction.

3. A slide fastener comprising in combination a pair of rows of interlocking elements, a slider having a passage for the rows and adapted when moved in one direction along the rows to interlock the rows to close the fastener, and when moved in the opposite direction along the rows to disengage the rows to open the fastener, a locking member movable longitudinally in the slider and adapted to project into the passage, means carried by the slider resiliently holding the locking member in a fixed position projecting into the path of the interlocking elements through the passage, means responsive to engagement of an element with the locking member and to subsequent longitudinal movement of the locking member in one direction in the slider for moving the locking member further into said path, means for moving the locking member in the opposite direction in the slider, and means responsive to longitudinal movement of the locking member in the opposite direction in the slider for moving the locking member out of said path.

4. A slide fastener comprising in combination a pair of rows of interlocking elements, a slider having a passage for the rows and adapted when moved in one direction along the rows to interlock the rows to close the fastener, and when moved in the opposite direction along the rows to disengage the rows to open the fastener, a locking member movable longitudinally in the slider and adapted to project into the passage, means carried by the slider resiliently holding the locking member in a fixed position projecting into the path of the interlocking elements through the passage, and inclined cam for mov-

ing the locking member further into said path in response to engagement of an element with the locking member and to subsequent longitudinal movement of the locking member in one direction in the slider, means for moving the locking member in the opposite direction in the slider and a second inclined cam for moving the locking member out of said path in response to movement of the locking member in the opposite direction.

5. A slide fastener comprising in combination a pair of rows of interlocking elements, a slider having a passage for the rows and adapted when moved in one direction along the rows to interlock the rows to close the fastener, and when moved in the opposite direction along the rows to disengage the rows to open the fastener, a locking member movable longitudinally in the slider and adapted to project into the passage, means carried by the slider resiliently holding the locking member in a fixed position projecting into the path of the interlocking elements through the passage, means responsive to engagement of an element with the locking member and to subsequent longitudinal movement of the locking member in one direction in the slider for moving the locking member further into said path, means for moving the locking member in the opposite direction in the slider, means responsive to longitudinal movement of the locking member in the opposite direction for moving the locking member out of said path, and a pull tab on the slider for moving the slider in the opening and closing directions, the tab being adapted to move the locking member in said opposite direction in the slider when the tab moves the slider in the opening direction.

6. A slide fastener comprising in combination a pair of rows of interlocking elements, a slider having a passage for the rows and adapted when moved in one direction to interlock the rows to close the fastener and when moved in the opposite direction to disengage the rows to open the fastener, a pair of locking members in the slider adapted to project into the passage from opposite sides, means carried by the slider resiliently holding the locking members in a fixed position projecting into the path of the interlocking elements through the passage, and means responsive to engagement of an interlocking element with the locking member and to subsequent initial movement of the slider in the opening direction for moving the locking members further into said path.

7. A slide fastener comprising in combination a pair of rows of interlocking elements, a slider embracing the rows, a pull tab for moving the slider along the rows either to interlock the rows to close the fastener or to disengage the rows to open the fastener, locking means in the slider adapted to engage one side of an interlocking element, second locking means connected to the first locking means and adapted to engage the other side of the element, both said locking means being normally in the path of the interlocking elements through the slider and being movable longitudinally of the slider, means connecting the pull tab to the first locking means for moving said first locking means longitudinally of the slider and out of said path, and means responsive to longitudinal movement of said locking means for moving the second locking means out of said path.

8. A slide fastener comprising in combination a pair of rows of interlocking elements, a slider

embracing the rows and having a passage through the slider for the interlocking elements, a pull for moving the slider along the rows either to interlock the rows to close the fastener or to open the fastener by disengaging the rows, a pair of connected locking members normally extending into the path of the interlocking elements through the slider, said locking members being movable longitudinally of the slider and being movable into and out of said path, means connecting the pull to one of the locking members for moving the members longitudinally of the slider and for moving both of the locking members out of the passage, and means responsive to longitudinal movement of the locking members for moving the other locking member out of said path.

9. A slide fastener comprising in combination a pair of rows of interlocking elements, a slider embracing the rows and having a passage through the slider for the elements, a pull for moving the slider along the rows either to interlock the rows to close the fastener or to disengage the rows to open the fastener, locking means in the slider adapted to project into one side of the passage, a second locking means connected to the first locking means and adapted to project into the opposite side of the passage, both locking means extending normally into the path of the interlocking elements through the slider, means connecting the pull to one of the locking means for moving both locking means longitudinally of the slider and for moving one locking means out of said path, a cam face on the second locking means and a cam on the slider for moving the second locking means out of said path in response to movement of the locking means longitudinally of the slider.

10. A slide fastener comprising in combination a pair of rows of interlocking elements, a slider embracing the rows and having a passage through the slider for the elements, a pull for moving the slider along the rows either to interlock the rows to close the fastener or to disengage the rows to open the fastener, a spring longitudinally movable in the slider and having a pair of arms extending on opposite sides of said passage, a locking member carried by each arm and normally positioned in the path of the interlocking elements through the passage, means connecting the pull to one arm of the spring for moving the spring longitudinally of the slider and for moving one locking member out of the passage, and means cooperating with the other arm of the spring for moving the other locking member out of the passage in response to longitudinal movement of the spring.

55

11. A slide fastener comprising in combination a pair of rows of interlocking elements, a slider embracing the rows and having a passage extending through the slider for the elements, a longitudinal guide in the slider, a pull for moving the slider along the rows either to interlock the rows to close the fastener or to disengage the rows to open the fastener, a forked member having the tail of the fork slidable in said longitudinal guide and having a pair of resilient arms extending on opposite sides of said passage, a locking member carried by each arm and normally extending within the passage, means connecting the pull to one of the arms for moving the forked member longitudinally of the slider and for moving one of the locking members out of the passage, and means cooperating with the other arm to move the other locking member out of the passage in response to longitudinal movement of the forked member.
12. A slide fastener comprising in combination a pair of rows of interlocking elements, a slider embracing the rows and having a passage extending through the slider for the elements, a pair of longitudinal guides in the slider, a pull for moving the slider along the rows either to interlock the rows to close the fastener or to disengage the rows to open the fastener, a resilient arm slidable in one guide, a locking member carried by the arm and normally held by the resilient arm in said passage, a second resilient arm connected to the first arm and disposed in the second guide, a second locking member carried by the second arm and normally positioned by the second arm within the passage, means connecting the pull to the first arm for moving the first locking member out of the passage and for sliding the arms in the guides and means responsive to sliding of the arms in the guides for moving the second locking member out of the passage.
